UNITED STATES PATENT OFFICE.

ELMIRE JENNINGS, OF NEW YORK, N. Y.

HOSE-SUPPORTER.

1,076,675.

Specification of Letters Patent.

Patented Oct. 28, 1913.

Application filed February 20, 1913. Serial No. 749,705.

To all whom it may concern:

Be it known that I, ELMIRE JENNINGS, a citizen of the United States, residing at New York, in the county of New York and State 5 of New York, have invented a new and useful Hose-Supporter, of which the following is a specification.

The present invention appertains to hose supporters, and aims to provide a novel and 10 improved device of this character, which shall be non-destructive in its character.

It is the object of the present invention to provide a device of the character indicated which shall be devoid of metallic parts for 15 engaging the hose, in order that the hose may not be torn or injured, it being a further object of the present invention to provide interengageable elastic or flexible parts for engagement with the hose in a novel 20 manner.

Another object of the present invention is to provide an article of manufacture of the nature indicated which shall be comparatively simple, and inexpensive in construction, as well as serviceable, convenient and efficient in its use.

With the foregoing and other objects in view which will appear as the description proceeds, the invention resides in the combination and arrangement of parts and in the details of construction hereinafter described and claimed, it being understood that changes in the precise embodiment of invention herein disclosed can be made within the 35 scope of what is claimed without departing from the spirit of the invention.

The preferred embodiment of the invention has been illustrated in the accompanying drawing, wherein:

40 Figure 1 is a perspective view of the supporter as applied to a hose. Fig. 2 is a perspective view thereof showing the same detached. Fig. 3 is a longitudinal sectional view of the device.

45 Referring specifically to the drawings, there is provided a metallic loop 4, through which the elastic 5 may be engaged. A flexible, but non-elastic tape is attached to the lower bar of the loop 4, the elastic 5 being 50 passed around the upper bar thereof, and the end of the tape being preferably bent or looped over the lower bar of the loop 4, as at 7. An elastic flap 8 of soft rubber or other elastic and flexible material is also 55 attached to the lower bar or loop 4, the same preferably having its end 9 looped or bent

over the lower bar of the loop 4 or over the loop or hem 7 of the tape 6. The respective ends of the tape and flap are made secure by means of a line stitches 10.

60 The free end of the strap 8 is preferably rounded and provided with a transverse elliptical or oval opening 11 and a bar or elongated knob or button 12 is attached to the free end of the tape 6. In attaching the 65 knob or button 12 to the tape, the knob or button is provided with a longitudinal slot 13 through which the end 14 of the tape is passed, the said end of the tape being bent back and made secure by a line of stitches 70 15. The bar or knob 12 is constructed of soft rubber, or other elastic and flexible material, and is of a length somewhat longer than the opening 11, the tape 6 also being preferably 75 slightly longer than the flap 8.

75 In attaching the supporter to a hose, the flap 8 is lapped over the outer side of the hose, and the bar or knob 12 suspended by the tape 6 is passed down the inner side of the hose, and is passed outwardly through 80 the opening 11 in the flap with the corresponding portions of the hose, as seen in Fig. 1. It is to be noted that the tape 6 permits the bar or knob 12 to be conveniently manipulated, and suspends the bar 85 from the loop 4.

85 Particular attention is directed to the fact that when the bar and respective portion of the hose is passed through the opening 11, the opening is adapted to expand so as to 90 accommodate the parts passed therethrough, and the bar or knob 12 is itself adapted to bend or flex so as to accommodate the engagement of the hose in a most effective and convenient manner. The hose will thus 95 engage between the elastic flap 8 and the elastic bar or knob 12, so that the said parts may yield to conform to the various conditions and in order not to tear or injure the hose, as would be liable to result if metallic 100 parts were employed. It is to be further noted, that the hose is connected to the loop 4 by the elastic flap 8, the flap being adapted to yield as well as the elastic 5, the tape 6, however, limiting the stretching or extension of the flap.

105 From the foregoing, taken in connection with the drawings, the advantages and capabilities of the present device will be apparent and it will be noted that the objects 110 aimed at have been carried out satisfactorily.

The present supporter will be non-destructive.

tive, irrespective of the strains that the supporter and hose may be subjected to. There is no tendency to cut or tear the hose, or to tear the button hole opening 11.

5. What is claimed as new is:—

1. In a hose supporter, an elastic flap having a transverse opening, a non-elastic tape, and a flexible bar having a longitudinal slot, the free end of the tape being passed through the said slot and secured upon itself.
2. In a hose supporter, a loop attachable to an elastic, a non-elastic tape, and an elastic flap having adjoining ends secured over

one part of the loop, the flap having a transverse oval opening adjoining its free end, and a flexible bar having a longitudinal slot, the free end of the tape being passed through the said slot and secured upon itself.

In testimony that I claim the foregoing as my own, I have hereto affixed my signature in the presence of two witnesses.

ELMIRE JENNINGS.
